CLAIM

The ornamental design for a vehicle door as shown and described.

DESCRIPTION

FIG. 1 is a front view of a first embodiment of a vehicle door of our present design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front left perspective view thereof;

FIG. 8 is a front view of a second embodiment of a vehicle door of our present design;

FIG. 9 is a rear view thereof;

FIG. 10 is a right side view thereof;

FIG. 11 is a left side view thereof;

FIG. 12 is a top view thereof;

FIG. 13 is a bottom view thereof; and,

FIG. 14 is a front left perspective view thereof.

The broken lines and deemphasized shading depict portions of the vehicle door that form no part of the claimed design.

1 Claim, 14 Drawing Sheets
